Primary Examiner — Susan Bennett Hattan*Assistant Examiner* — Brett Miller(74) *Attorney, Agent, or Firm* — Hodgson Russ LLP(57) **CLAIM**

The ornamental design for beverageware, as shown and described.

DESCRIPTION

FIG. 1 is a perspective view of the beverageware showing my new design with an exemplary lid;

FIG. 2 is a perspective view thereof with the exemplary lid of the beverageware removed;

FIG. 3 is a front view thereof, the rear, left-side, and right-side views forming a mirror image thereof;

FIG. 4 is a top view thereof; and,

FIG. 5 is a bottom view thereof.

The broken lines illustrate portions of the beverageware and form no part of the claimed design.
